ATTORNEYS

UNITED STATES PATENT OFFICE

MATHIAS REH, OF NEW YORK, N. Y.

BRUSH

Application filed January 15, 1931. Serial No. 509,007.

This invention relates to new and useful improvements in brushes such as clothes brushes or shoe brushes, and has among its several objects to provide a brush having a readily accessible compartment for carrying various accessories such as a shoe horn, a button hook, needles, thread, thimble, and so forth, or a tube of shoe polish and a shoe shining rag; to provide such a brush which is composed of but few parts and is therefore simple in construction and cheap to manufacture.

In the accompanying drawings:

Figure 1 is a perspective view of a brush constructed in accordance with my invention;

Figure 2 is a vertical longitudinal section therethrough; and

Figure 3 is a vertical cross section thereof.

Referring to the accompanying drawings, my invention comprises a brush such as a clothes brush or a shoe brush which includes a back A formed from a sheet of relatively stiff material such as celluloid and pressed to form a bottom 5, sides 6-6, and ends 7-7, the bottom being formed with a plurality of openings 8. Disposed within the hollow back A is a receptacle B which is formed from a sheet of relatively stiff material such as celluloid and includes a bottom 9, side walls 10-10, and end walls 11-11. This receptacle, like the back A, is pressed into shape and is nested within said back, the side walls 10-10 bearing against the side walls 6-6 of the back and the end walls 11-11 bearing against the end walls 7-7 of the back. The bottom 9 of the receptacle B is pressed above the bottom 5 of the back, and located therebetween is a block 12 of plastic material. A plurality of bristles 13 extends outwardly through the openings 8 of the back and have their inner ends firmly anchored in the plastic block 12. The upper edges of the back A and the receptacle B are disposed in flush relation. A cover C which is also from a sheet of relatively stiff material such as celluloid is pressed into shape to form a top 14, side walls 15-15, and end walls 16-16. The cover C fits over the back A and the walls of said cover frictionally engage the outer faces

of the walls of the back. A bead 17 is secured to the outer faces of the walls of the back and is located centrally between the upper and lower edges of the side and end walls thereof. The bead 17 functions to limit the closing movement of the cover.

The side walls 10-10 and end walls 11-11 of the receptacle B are rigidly secured to the adjacent walls of the back by any suitable means.

From the foregoing it will be observed that I have provided a brush having a readily accessible receptacle for containing various accessories, and which is extremely simple in construction and is cheap to manufacture.

I claim:

In a brush, the combination with a hollow back consisting of relatively stiff material and having a perforated bottom; of a receptacle consisting of relatively stiff material and having a bottom, said receptacle being nested within the hollow back and rigidly secured thereto with the bottom of the receptacle spaced above the bottom of the back; a block within the back and below the bottom of the receptacle; a plurality of bristles extending outwardly through the perforations of the bottom and having their inner ends secured in said block; and a removable cover for the back and receptacle frictionally engaging the outer faces of the side walls and end walls of the back.

In testimony whereof, I have hereunto subscribed my name.

MATHIAS REH.
